GUILLERMO ROVIROSA, OF BARCELONA, SPAIN

MECHANICAL TOY

Application filed August 10, 1928, Serial No. 298,731, and in Spain August 19, 1927.

The invention consists in a toy the mechanism of which is intended to carry out certain movements analogous to those made by the vast majority of quadrupeds when walking.

The present invention relates to toys imitative of any quadruped and in which leg movements simulating the natural leg movements of the quadruped are reproduced with realism when the toy moves or is moved over a suitable surface.

According to the present invention, the leg portions of a toy of this kind are mounted upon cranks at the opposite extremities 15 of front and rear axles extending transversely of a body portion representative of the body of the quadruped and are each operatively connected also with a further crank mounted on the body portion at a point above 20 the adjacent axle and rearwardly of the adjacent axle by an amount in inverse proportion to the step to be taken by the leg portions.

The movement is obtained when the toy 25 is drawn by a string or other similar device so that it tends to be dragged, or by producing by any means a rotary movement of the rotating parts described hereunder.

In order that the invention may be clearly 30 understood and readily carried into effect reference may now be had to the accompanying drawings illustrating the invention by way of example and in which:—

Fig. 1 is a sectional plan;

Fig. 2 is a side view;

Fig. 3 is a transverse section;

Fig. 4 is a diagrammatic or schematic representation of the movement; and

Fig. 5 is a longitudinal section of the toy.

In giving a description of the toy, two parts of the latter must be distinguished, viz. the body, and the legs and feet.

The body constitutes the frame sustaining 45 and protecting the mechanism. The legs are the movable parts, which are coupled to the mechanism and, upon moving, give the impression of the real movement as made by live quadrupeds when walking.

The body may be made of any material

that lends itself thereto, such as metal stampings, wood, papier mâché, rags, etc., the same being adapted to the form of the animal to be imitated, the only requisites being that it should be sufficiently hollow inside to house 55 the mechanism and support thereof and that where the four legs are joined to the trunk, the latter should present a plane surface (two on each side), the surfaces of one and the same side being situated on the same plane; 60 and the surfaces on opposite sides, on parallel planes. These lateral plane surfaces of the trunk are to be sufficiently large to afford free play to the legs when they move and walk.

On each of these four plane surfaces there are two circular holes or openings. The lower opening houses a metal axle 1, which projects from either side of the trunk. These axles, viz. the front and rear or hind one, 70 are provided in their middle, in the inside of the trunk, with two eccentrics set at 90° (right angle) the one to the other, all four being of the same eccentricity or throw. The eccentrics of the front axle are joined to 75 those of the hind axle by two connecting rods 3, whereby the synchronous movement of both axles is assured. The throw or degree of eccentricity and dimensions of these parts (except the connecting rods) are unspecified, as 80 the only purpose they serve is to ensure that the rotative movement of the fore or front and hind axles shall be uniform. The same result might be secured by fitting the centre of the axles with identical toothed wheels 85 joined together by an endless chain; or bevel gears might be used, connecting the two axles by a longitudinal shaft.

The axles 1, at their ends outside the trunk, are fitted with cranks. The cranks situate at 90 the ends of one and the same axle are set at an angle of 180°, the one to the other, i. e. they are diametrically opposed. The cranks situate on one and the same side of the trunk are also set at angles of 180°, or diametrically 95 opposed one to another. Thus the rotation of any one of the cranks synchronizes with that of the crank of the other axle situate on the opposite side. The eccentricity of these cranks may vary with the size of the toy and 100

their size is what mainly influences the height to which the feet are raised from the ground at the moment of advancing.

The circular openings 2 are situate behind and above the line joining the axles 1 at a height approximately equal to double the eccentricity of the cranks described above. The distance between the openings 2 is the same as the distance between the axles 1. At each of the four openings 2 an independent crank is lodged, and the eccentricity of all these cranks is practically equal to double that of the cranks 1.

The distance between the axles 1 and the cranks 2 may be fixed as desired, it being understood that the less this distance is the larger is the step taken by the toy animal, and vice-versa.

The legs are to be of wood, cork agglomerate, or other suitable material, of sufficient thickness to ensure that, on being coupled to the cranks, they are firmly held by the cranks 1, which latter are fitted at the end with pins or washers or are burred over or otherwise formed, to prevent the legs slipping off.

The legs may be of any shape, adapted to those of the animal that is imitated, but three essential points have to be located on them, viz: *a* the point of connection of the leg with the crank 1; *b* the point of connection of the leg with the crank 2; and *c* the point of support on the ground. These three points determine the vertices of an isosceles triangle, the base of which is *ab*. The height may be greater or less, according to the length of the legs of the animal to be imitated. The distance *ab* is equal to the distance between the horizontal projections of the axles 1 and openings 2, plus the eccentricity of the crank 1.

The working will be understood by a consideration merely of the four cranks 1 (cf. the schematic drawing); the four cranks 2; and the four triangles *abc*. Let a moment be supposed when all four legs rest on the ground or surface. When movement is produced by drawing the toy, owing to the natural adherence of the points of support *c* on the ground or surface, all the legs will tend to cause the cranks 1 to rotate in the direction of the arrows shown on the schematic drawing. In their movement the points *c* follow the trajectory shown on the drawing. Thus, when the movement begins, the toy at once only rests on the near fore, and off hind, leg and on the point by which it is drawn; whilst the two other legs move forward without resting on the ground until, on reaching the end of their progression they descend sufficiently, whilst the others rise, for all four legs to rest on the ground simultaneously; and the movement continues thus indefinitely. Naturally in the toys the legs do not rest on a point, but on a surface imitating the sole of the foot.

65 The vertex *c* of the isosceles triangle *abc* will

then be at the rearmost part, or heel, of that surface. This will even facilitate movement, as thereby when all four feet are on the ground, *a* (see drawing) is a little further advanced in the direction of the arrow.

It will be readily understood that if by any mechanical means the cranks 1 are made to rotate in the direction of the arrow, the toy also will advance, though its progress will not be so sure as if it were drawn, as the point of support by which it is drawn will then be lacking.

Having in the above sufficiently described my invention and the manner in which it is to be performed, what I seek to have protected by patent as being of my own invention are the following claims:

1. A toy formed so as to represent any natural quadruped comprising a body portion and leg portions, front and rear axles extending transversely of said body portion, cranks at the opposite extremities of said front and rear axles, said leg portions being mounted on said cranks, further cranks mounted one on each side of the body portion at a point above each axle and rearwardly thereof, each of said leg portions being operatively connected to one of said further cranks whereby the leg movements of the natural quadruped are imitated when the toy is moved over a suitable surface.

2. A toy as claimed in claim 1 in which the throw of said further cranks is equal approximately to twice the throw of the cranks at the extremities of the axles and each of said cranks is mounted upon the body portion above the adjacent axle by an amount equal to its throw.

In testimony whereof, I affix my signature.

GUILLEMMO ROVIROSA.
